DESIGN FOR A PRY-OFF TYPE CONTAINER CAP REMOVING TOOL

Lawrence P. Frettoloso, Brooklyn, N. Y., assignor
to Udall & Landan Manufacturing Co. Inc.,
New York, N. Y., a corporation of New York

Application January 4, 1947, Serial No. 135,942

Term of patent 3½ years

(Cl. D44—29)

To all whom it may concern:

Be it known that I, Lawrence P. Frettoloso, a citizen of the United States of America, residing at Brooklyn, Kings County, and State of New York, have invented a new, original, and ornamental Design for a Pry-Off Type Container Cap Removing Tool, of which the following is a specification, reference being had to the accompanying drawing, forming part thereof.

Fig. 1 is a perspective view showing one side of a pry-off type container cap removing tool, embodying my design.

Fig. 2 is a perspective view showing the reverse side of the pry-off type container cap removing tool.

Fig. 3 is a cross-sectional view of the pry-off

type container cap removing tool taken on the plane of the line 3—3 of Fig. 1.

I claim:

The ornamental design for a pry-off type container cap removing tool, as shown.

LAWRENCE P. FRETTOLOSO.
